CARD TABLE RACK

William Ray Kiefer, Rockford, Ill.

Application August 16, 1933, Serial No. 685,375

11 Claims. (Cl. 312—173)

The invention relates to a rack for supporting a card table or the like in an out-of-the-way position on the back of a horizontally swinging door.

Most inside doors in residences and particularly closet doors, which afford a convenient place for storing card or similar tables, are generally narrower than the table so that the table cannot readily be supported thereon without interfering with the closing of the door.

It is a primary object of the invention, therefore, to provide a rack for supporting a folded table on a horizontally swinging door in a manner so that the table will not interfere with the closing of the door even though it may be wider than the door on which it is mounted.

Another object of the invention is to provide a rack of the character described which supports a table wider than the door in a position parallel with and closely adjacent the door when the latter is open so as to permit unobstructed passage through the doorway and which swings the projecting edge of the table away from the door in closing so that the table will not abut the door casing or the closet wall.

The invention also resides in the adjustable character of the support which permits one or a plurality of tables to be mounted on the door and also in the novel character of the means for holding the table correctly positioned.

Yet another object is to provide a table supporting rack of the character described which is easily converted to adapt it to be attached to a right-hand or a left-hand swinging door.

Other objects and advantages will become apparent from the following detailed description taken in connection with the drawing illustrative of a practical embodiment of the invention, and in which

Figure 1 is a perspective view of a card table rack, embodying the features of the invention, mounted on a door. The rack is shown with the door in open position.

Fig. 2 is an enlarged detail view of the link for swinging the rack.

Fig. 3 is a top plan view of a rack supporting three tables and mounted on a door shown in open position.

Fig. 4 is a view similar to Fig. 3 but showing the position of the rack when the door is in closed position.

Fig. 5 is a horizontal sectional view taken approximately along the line 5—5 of Fig. 1.

Fig. 6 is a view similar to Fig. 4 but showing the rack mounted on a left hand swinging door.

Fig. 7 is a view similar to Fig. 6 illustrating the

application of the rack to the door of a narrow closet.

The rack shown in the drawing for purposes of disclosure is composed of a substantially flat frame 10 intended to be secured on the back of a door 9 and having means for securing thereon in vertical position one or more folded tables 11 of greater width than the door. In order that the door may swing to closed position when tables of such width are supported on the rack, the rack 10 is mounted on the door in such a manner that one vertical edge of the tables will be spaced from the free edge of the door a distance sufficient to clear the door jamb while the opposite vertical edges will project beyond the hinged edge of the door but will in the closed position of the latter, overlap or project in beyond the casing 13 to which the door is hinged. This is accomplished by constructing the rack so that in the closed position of the door, the frame 10 will extend at an angle 15 to the door as shown in Figs. 4, 6 and 7. While the frame may be attached in a manner such as to maintain this angular relationship of the table and the door in all positions of the latter, it is preferred to move the rack relative to the door 20 as an incident to closing of the latter so that in the open position, the tables will extend parallel with the door as shown in Fig. 3 and thereby avoid obstructing free passage through the doorway.

Herein such actuation of the rack relative to the door is accomplished by pivoting the frame 10 to the door to swing about a vertical axis adjacent the free edge of the door and providing means capable of imparting the desired movement to the frame as the door is swung from one position to the other. To this end, an elongated vertical side edge of the frame 10 is attached to the back of the door near the free edge of the latter by means of hinges 18 widely spaced apart so that the rack will provide the desired rugged support. Swinging of the frame in accordance with the movements of the door is produced by a link 19 pivotally connected at one end to the door casing as indicated at 20 or to the wall as shown in Fig. 7, the other end being pivotally connected to the free edge of the frame.

The connection provided by the link 19 is adjustable so as to obtain that swing of the frame which is necessary for the table to clear the door casing. Such adjustment connection is obtained by forming in a cross-member 16 a horizontal slot 21 adapted to receive a bolt 22 pivoted on the end of the link 19. Washers 23 spaced on opposite sides of the member 16 and a nut 24 threaded onto

the bolt complete the construction whereby the link 19 may be attached to the frame at varying distances from the hinge axis and thus vary the swing imparted to the frame as may be necessary

5 in adapting the rack to different widths of doors and constructions of door casings. Preferably, the link 19 is bent slightly, as best seen in Figs. 3 and 4, in order to extend around the edge of the door when the same is in open position.

10 Means providing a horizontal ledge for supporting the table in vertical position from its lower edge is attached to the rack. In the present instance, this means comprises a pair of U-shaped and horizontally projecting arms 25, horizontally

15 spaced along the lower edge of the frame 10. One leg of each of the arms projects upwardly through an aperture boss 27 on the bottom member of the frame and is threaded to receive a nut 28 by means of which it is retained in the boss. The 20 other leg constitutes a stop for preventing the tables from sliding off of the arm. Preferably, the arms 25 are frictionally held against swinging and thus may be swung into different angular positions relative to the frame according to the 25 number of tables to be supported thereon.

For the purpose of holding the upper edge of the tables in against the frame during swinging of the door, a single forwardly projecting arm 26 having a depending outer end is employed, preferably being located near the center of the door. To permit the arm to be raised for insertion or removal of a table from the rack, the arm is, in the present embodiment, rigid with the end of a rod 31 extending through aligned bosses 30 in the 35 upper and intermediate cross-members of the frame 10 with its lower end pivotally and detachably secured to a yoke 32, the legs of which are guided in bosses 34. A compression spring 35 coiled about the rod 31 and acting between the 40 yoke and the adjacent boss 30 constantly urges the arm 26 downwardly against the upper edge of the table and creates the friction necessary for holding the arm in the desired angular position. The arm 26 may be lifted conveniently by 45 grasping a handle 37 thereon.

Bosses 36 located similarly to the bosses 34 are provided to enable the rod 31 to be mounted in the same position when the frame 10 is inverted for application of the rack to a right hand door (see Fig. 6). The application to such a door also 50 requires removal of the arms 25 and mounting thereof in bosses 38.

The arms 25 and 26 and a stop pin 39 for limiting the movement of the tables toward the 55 free edge of the door are covered with rubber or other tubing to avoid marring of the table finish.

In the application of the rack above described to doors hinged to relatively wide casings, it is merely necessary for the link 19 to be adjusted 60 so that the table will clear the casing. However, when the rack is applied to a door assembly wherein a wall is disposed close to the door axis, the link must be adjusted so as to throw the free edge of the table farther away from the door as 65 the latter is closed thereby clearing the wall.

I claim as my invention:

1. A rack for mounting on the back of a horizontally swinging door a folded table of a width greater than the door comprising a frame secured 70 to the back of the door and providing a horizontal support mounted on the back of the door for supporting the table in vertical position and means attached to said frame and acting, when the door is in closed position, to position one vertical side edge of the table adjacent the free edge

of the door and to space the opposite edge a distance from the hinged edge of the door sufficient to clear the casing to which the door is hinged or an adjacent wall when the door is closed.

2. A rack for mounting on the back of a horizontal swinging door a folded table of a width greater than the door comprising, a frame mounted on the back of a door and supporting the entire weight of said table, and means acting when the door is closed to position the table 10 at an angle to the door with one vertical side edge disposed within the confines of the door and the opposite vertical side edge projecting beyond the hinged edge of the door.

3. A rack for mounting on the back of a horizontally swinging door a folded table of a width greater than the door comprising, a frame of a width narrower than the door secured to the back thereof and providing a horizontal support for sustaining the weight of said table when disposed alongside of the door, and means operatively connected to said frame and positioning the table with one vertical side edge disposed close to the door adjacent the free edge thereof and the other side edge projected beyond and spaced from the hinged edge of the door when the latter is in closed position.

4. A rack for mounting on the back of a horizontally swinging door a folded table of a width greater than the door comprising a frame pivoted 30 on the back of the door to swing relative thereto about a vertical axis disposed adjacent the free edge of the door, means on said frame for supporting the table in vertical position alongside of the door when the latter is open, and means 35 acting on said frame automatically in the closing of the door to move the free edge of said frame away from the hinged edge of the door.

5. A rack for supporting upon the back of a door a folded table wider than the door comprising 40 a frame, means carried by the frame for supporting the table thereon in vertical position, said frame being swingably mounted on said door to support the table with one vertical edge projecting beyond the hinged edge of the door, and 45 means operable as an incident to the opening of the door to swing said frame to and position said table substantially parallel with the door and operable as an incident to the closing of the door to swing the frame away from the hinged edge 50 of the door so that the projecting edge of the table will clear the door casing.

6. A rack for supporting on the back of a door a table wider than the door comprising, a frame hinged at one vertical edge near the free edge of 55 the door and having the opposite end free to swing toward and away from the hinged edge of the door, means for supporting a table on the frame with one edge projecting beyond the hinged edge of the door, and a link connected at one end to a fixed pivot adjacent the hinge axis of the door and at the other end to the free end of the frame and operable to swing the frame from a position substantially parallel with the door when the door is open to a position at an angle with the door 60 when the door is closed.

7. A rack for supporting on the back of a door a table wider than the door comprising, a frame hinged at one vertical edge near the free edge of 70 the door and having the opposite end free to swing toward and away from the hinged edge of the door, means for supporting a table on the frame with one edge projecting beyond the hinged edge of the door, a link connected at one end to a fixed pivot adjacent the hinge axis of the door 75

and at the other end to the free end of the frame and operable to swing the frame from a position substantially parallel with the door when the door is open to a position at an angle with the door 5 when the door is closed, the connection between the link and the frame being adjustable along the frame toward and from the pivotal axis of the latter whereby to vary the movement imparted to the frame in opening and closing of the door.

10 8. A card table supporting rack to be mounted on a door comprising a frame mounted on the door in vertical position and means for securing a table to the frame comprising a pair of arms projecting from the lower edge of the frame for supporting a table in vertical position from its lower edge and a retaining arm overlying the upper edge of the table to hold such edge against the frame, said arms being pivoted on the frame 15 to swing horizontally whereby to adapt the rack for supporting one or a plurality of tables.

9. A rack for supporting one or more folded card tables on the back of a door comprising a frame adapted to lie against and be secured from 20 the back of the door, and a pair of arms mounted on said frame and projecting horizontally away from the frame for supporting a table from its lower edge, said arms having outer upturned ends 25 adjustable toward and away from the frame

whereby one or more tables may be accommodated and held in fixed relation to the frame.

10. A rack for supporting on the back of a door a table wider than the door comprising, a frame hinged at one vertical edge near the free edge of the door and having the opposite end free to swing toward and away from the hinged edge of the door, means for supporting a table on the frame with one edge projecting beyond the hinged edge of the door, and a link having one end 10 pivotally connected to the free edge of said frame, the intermediate portion bent and extending around the hinged edge of the door and the opposite end pivoted to a fixed point adjacent the hinge axis of the door. 15

11. A rack for supporting a folded card table on the back of a horizontally swingable door comprising, in combination, a frame lying against and secured to the door on the back thereof and mounted thereon in a predetermined relation with 20 respect to the hinged edge of the door, and a structurally separate member mountable on said frame interchangeably in two different positions according to which side edge the door is hinged from, said member providing a horizontal support projecting from said frame away from the door and adapted to sustain the weight of said table. 25
